UNITED STATES PATENT OFFICE.

HENRY G. JOHNSON, OF EAST HAMPTON, CONNECTICUT, ASSIGNOR TO SUMMIT THREAD COMPANY, OF EAST HAMPTON, CONNECTICUT, A CORPORATION OF MAINE.

SEWING-MACHINE SHUTTLE.

Application filed June 21, 1922. Serial No. 569,889.

To all whom it may concern:

Be it known that I, HENRY G. JOHNSON, a citizen of the United States, residing at East Hampton, in the county of Middlesex and State of Connecticut, have invented new and useful Improvements in Sewing-Machine Shuttles, of which the following is a specification.

This invention relates to a rotary shuttle which includes a flat sided circular body portion, and an annular wall projecting from one side of the body portion and rotatable therewith, the body portion and wall forming a bobbin chamber which is closed at one end by the body portion, and open at the opposite end, and a post secured to the body portion, and occupying the center of the bobbin chamber to form a bearing on which a bobbin, located in said chamber, may rotate.

The object of the invention is to enable a ready wound bobbin composed of a tubular core or cop tube and an annular winding of thread thereon, to be used advantageously, in a shuttle characterized as above stated.

The invention is embodied in the improvements hereinafter described and claimed.

Of the accompanying drawings forming a part of this specification:

Figure 1 is a side view of a shuttle embodying the invention, the bobbin being removed.

Figure 2 is a section on line 2—2 of Figure 1.

Figure 3 is a view similar to Figure 2 showing the bobbin in place.

Figure 4 is a sectional view of the post.

Figure 5 is a sectional view of the flanged tube hereinafter described.

Figure 6 is a perspective view of the tube.

Figure 7 is a perspective view of a ready wound bobbin.

The same reference characters indicate the same parts in all of the figures.

In the drawings, 12 represents the flat sided circular body portion of a rotary shuttle, such as is used in the well known "Standard" sewing machine. Fixed to and projecting from one side of the body portion is an annular wall 13, said body portion and wall forming a circular bobbin chamber, which is closed at one end by the body

portion 12, and is open at the opposite end. 14 represents a cylindrical post which is a tube, the bore of which is open at the outer end of the post. The inner end of the post is formed by a head 15, having an orifice receiving an attaching screw 16 whereby the post is secured to the body portion 12.

The construction thus far described embodies nothing new, and it should be understood that the entire construction shown by the drawing and not hereinafter described, and the general operation of a shuttle embodying said construction are well known.

In carrying out my invention, I modify the form of the post, and combine therewith a flanged sleeve, as next described.

The outer end of the post is provided with a peripheral enlargement forming an inwardly facing annular stop shoulder 18 of greater diameter than the portion of the post between said enlargement and the inner end of the post. 19 represents a tube to one end of which is fixed a flat sided annular flange 20. The tube 19 is formed to have a frictional fit on the post 14, the length of the tube being such that its outer end contacts with the stop shoulder 18, and its flange 20 contacts with the body portion 12, the tube and flange being confined in the bobbin chamber by the stop shoulder.

The diameter of the tube is such that its periphery is substantially flush with the periphery of the enlargement forming the stop shoulder, so that the core or cop tube 21 of a ready wound bobbin is adapted to be pressed onto the post and tube, and withdrawn therefrom.

When the bobbin is fully inserted in the chamber, one end of the thread winding 22 of the bobbin contacts with the flange 20. The core 21 is formed to have a close frictional fit on the tube 19, so that the bobbin and tube rotate together as the thread is drawn from the bobbin.

The tube, while fitting the post more loosely, has a sufficient frictional engagement with the post to prevent undesirably loose and free rotation of the tube and the bobbin. The flange 20 is of greater diameter than the bobbin, so that the thread cannot be caught between the inner end of the bobbin and the body portion 12 of the shuttle. The frictional contact of the flange with the body portion aids in preventing loose rotation of the bobbin. It will be understood

that the tube 19 is placed on the post before the latter is attached by the screw 16 to the body portion 12.

I claim:

- 5 A sewing machine shuttle comprising a body portion having formed therein a circular bobbin chamber open at one end, a sleeve, adapted to have a bobbin core slipped thereover, arranged within said chamber and provided at its inner end with an annular flange of substantially the same diameter as the chamber, a post extending through
- 10

said sleeve and having a socket extending inward from its outer end and provided within the bobbin chamber with an annular shoulder against which the outer end of the sleeve abuts, and a screw, having its head within the socket in the post, extending through the inner end of the post and securing it against the closed end of the bobbin chamber.

In testimony whereof I have affixed my signature.

HENRY G. JOHNSON.
